UNITED STATES PATENT OFFICE.

SAMUEL G. FOSTER, OF WESTFIELD, NEW JERSEY.

ADJUSTABLE WINDOW-SCREEN.

1,393,616.

Specification of Letters Patent. Patented Oct. 11, 1921.

Application filed February 25, 1921. Serial No. 447,696.

To all whom it may concern:

Be it known that I, SAMUEL G. FOSTER, a citizen of the United States, residing at Westfield, in the county of Union and State 5 of New Jersey, have invented certain new and useful Improvements in Adjustable Window-Screens; and I do declare the following to be a full, clear, and exact description of the invention, such as will enable 10 others skilled in the art to which it appertains to make and use the same.

This invention relates to improvements in adjustable window screens and more particularly to an improvement over the construction disclosed in United States Patent 1,022,312 of April 2nd, 1912. In the patented device a screen frame was provided consisting of four rectangular sections telescopically engaged with each other, a sheet 20 of woven wire having diagonal strands, was received at its edges in channels of said frame sections, and rivets were employed at spaced points for securing the screen to the frame. In actual practice, these rivets have 25 been found to greatly injure the wire mesh and to also interfere with smooth adjustment of the screen to different sizes and shapes. The principal object of my invention therefore is to devise a novel construction for anchoring the screen wire to the sectional frame, without the use of any rivets or like fasteners, the arrangement being such that the sheet of wire mesh is connected with the frame substantially throughout 30 its perimeter.

The patent above discussed included a pair of crossed brace bars which were pivoted together at their crossing point and also pivoted to the corners of the angular frame 40 sections. This construction has not proven entirely satisfactory and a further aim therefore is to provide an improved construction for retaining the brace bars in proper relation with the corners of the frame, without the necessity of employing any pivots.

With the foregoing and minor objects in view, the invention resides in the novel construction and arrangement of parts herein- 50 after described and claimed, the descriptive matter being supplemented by the accompanying drawings.

Figure 1 is an elevation of a screen constructed in accordance with my invention, 55 showing the same extended horizontally.

Fig. 2 is a view similar to Fig. 1 illustrating

the manner in which the screen may be extended vertically.

Fig. 3 is an enlarged vertical sectional view through one corner of the screen. 60

Fig. 4 is an enlarged horizontal sectional view as indicated by line 4-4 of Fig. 2.

Fig. 5 is a view similar to Fig. 4, as indicated by line 5-5 of Fig. 3.

In the drawings above briefly described, 65 the numerals 1 designate four right angular frame sections whose arms are telescopically connected to provide a complete rectangular frame which may be adjusted both vertically and horizontally. Each frame section 1 is of 70 substantially rectangular form in transverse section as shown in Figs. 4 and 5, one side thereof however, being longitudinally split as shown at 2, providing a relatively wide side flange 3 and a narrower flange 4 spaced 75 outwardly therefrom to a slight extent. The sheet of screen wire 5 passes between the flanges 3 and 4 through the split or slot 2 and the edges of said sheet are abruptly bent as shown at 6 so as to hook around the 80 flanges 3, thereby connecting the screen wire with the frame sections 1, substantially throughout the perimeter of the former. This provides a much more effective anchorage than the rivets disclosed in the patent above referred to and insures much 85 easier operation.

At the four corners of the screen, the diagonal strands 7, which strands are free of attachment to each other, are cut off as indicated at 8, providing for the necessary movement of said strands as the frame is adjusted.

In some positions of this frame, the cut away corners of the screen wire might 90 form openings allowing flies and other insects to enter, but in order to prevent this, I provide four right angular corner clips 9 having parallel side flanges 10 between which the corners of the frame sections are 95 soldered or otherwise secured. The flanges 100 10 extend inwardly from the inner corners of the frame sections, sufficiently to close any openings which might be formed in the manner above set forth and it will be seen that the clips 9 also serve to effectively brace the 105 frame sections. Furthermore, these clips act to retain the ends of crossed brace bars 11, in the inner corners of the frame sections 1, making it unnecessary to use pivots such as those disclosed in the patent above discussed. 110 One pivot 11' however is employed at the point where the bars 11 cross each other.

By employing the features of construction shown and described, a much more desirable and practical screen is provided, than that disclosed by Patent 1,022,312 and this screen 5 may be extended either vertically or horizontally without any binding of the frame sections or tearing of the wire.

Since excellent results are obtainable from the details disclosed, such details are preferably followed, but within the scope of the 10 invention as claimed, numerous minor changes may be made.

I claim:

1. An adjustable window screen comprising a frame formed of adjustably connected 15 sections having longitudinal channels jointly extending around the entire frame, and a sheet of woven wire having diagonal strands free of attachment to each other, the edges of 20 said sheet being abruptly bent into said channels and hooked over one side thereof in sliding engagement therewith.

2. An adjustable window screen comprising a frame formed of adjustably connected 25 sections, said frame sections being hollow and having longitudinal slots at one side of the frame, and a sheet of woven wire having diagonal strands free of attachment to each other, the edges of 30 said sheet being abruptly bent through said slots and hooked slidably around the portions of the frame sections at one side of said slots.

3. An adjustable window screen comprising a frame formed of adjustably connected 35 frame sections, each frame section being hollow and of substantially rectangular form in transverse section with one side

longitudinally split to form relatively wide and narrow side flanges, the latter being outwardly offset from the former, and a sheet 40 of woven wire having diagonal strands free of attachment to each other, the edges of said sheet being abruptly turned into the above mentioned split of each frame section and hooked slidably around the relatively 45 wide flange thereof.

4. An adjustable window screen comprising four right angular frame sections slidably engaged with each other to form a rectangular frame, a sheet of woven wire connected at its edges with said frame and having diagonal strands free of attachment to each other, nonextensible crossed braces pivoted together and having their ends located in the inner corners of said frame sections, 55 and braces for the corners of said frame sections serving to retain said brace ends in said corners.

5. An adjustable window screen comprising four right angular frame sections slidably engaged with each other to form a rectangular frame, a sheet of woven wire connected at its edges with said frame and having diagonal strands free of attachment to each other, non-extensible crossed braces 60 pivoted together and having their ends located in the inner corners of said frame sections, and corner clips secured on the corners of said frame sections and having side flanges retaining said brace ends in said corners. 65

In testimony whereof I have hereunto set my hand.

SAMUEL G. FOSTER.
